[57] **CLAIM**

The ornamental design for a hand-held optical character recognition reader, substantially as shown and described.

DESCRIPTION

FIG. 1 is a top plan view of a hand-held optical character recognition reader in accordance with my new design;

FIG. 2 is a right side elevational view of the hand-held optical character recognition reader shown in FIG. 1, the left side, not shown, being a mirror image thereof; FIG. 3 is a rear elevational view of the hand-held optical character recognition reader shown in FIG. 1; FIG. 4 is a front elevational view of the hand-held optical character recognition reader shown in FIG. 1; and

FIG. 5 is a bottom plan view of the hand-held optical character recognition reader shown in FIG. 1.
